UNITED STATES PATENT OFFICE.

LANSING ONDERDONK, OF NEW YORK, N. Y., ASSIGNOR TO UNION SPECIAL MACHINE COMPANY, OF CHICAGO, ILLINOIS, A CORPORATION OF ILLINOIS.

LOOPER-OPERATING MECHANISM FOR SEWING-MACHINES.

1,122,025.

Specification of Letters Patent. Patented Dec. 22, 1914.

Application filed November 2, 1908. Serial No. 460,708.

To all whom it may concern:

Be it known that I, LANSING ONDERDONK, a citizen of the United States, residing at New York city, in the county of New York, 5 State of New York, have invented certain new and useful Improvements in Looper-Operating Mechanism for Sewing-Machines, of which the following is a description, reference being had to the accompanying 10 drawing, and to the letters and figures of reference marked thereon.

My invention relates to new and useful improvements in looper operating mechanism for sewing machines, and has for its 15 object to provide a mechanism for operating a looper back and forth in a single plane, which mechanism is so constructed as to give a positive movement to the looper with a dwell at each end of its stroke, 20 whereby the stroke of the looper may be very short and the looper may move quickly from one end of its stroke to the other.

A further object of the invention, is to provide a looper which is mounted on a 25 vertical shaft and moves back and forth in a single plane, with mechanism for operating the same positively, and directly from the end of a shaft, located substantially at right angles to the looper shaft.

30 Still further objects of the invention will in part be obvious and will in part be hereinafter more fully described.

In the drawings which show by way of illustration, one embodiment of the invention; Figure 1 is a front view with parts broken away showing a sewing machine with my improved looper operating mechanism applied thereto. Fig. 2 is a bottom plan view of the same. Fig. 3 is a perspective view showing the looper and its immediate operating mechanism. Fig. 4 is an enlarged end view of the looper and its operating mechanism.

40 The bed plate 1 has rising therefrom, an 45 overhanging arm 2 in which reciprocates a needle bar 3. These parts are however, of the usual construction and will not need further description.

50 Mounted in the overhanging arm is a 50 rotating shaft which is operated by the usual belt wheel 4. Said operating shaft is geared to a lower rotating shaft 5 by means of a belt 6. Said lower rotating shaft 5 is mounted in suitable bearings 7, 8, and 9.

55 The looper 10 as herein shown, is of the

thread carrying type and is mounted on the end of the vertical shaft or looper support 11. Said looper support is carried by spaced bearings 12 and 13, which are formed in the ends of arms extending from the bracket 15 60 secured to the under side of the work support by suitable screws 16, which pass through slots in the bracket so that said bracket may be adjusted.

The looper shaft or support 11, is held 65 from longitudinal movement in its bearing by means of the collars 17 and 18. Said looper support is slightly flattened at 19 and an arm 20 which is forked at its inner end, straddle said flattened portion of the looper 70 support and is secured thereto by a pivot bolt 21. This connection between the arm 20 and the looper support, allows the arm to swing freely up and down in a vertical plane, but all movements of the arm in a 75 horizontal plane will impart a horizontal movement to the looper shaft or support.

On the forward end of the main shaft 5, 80 is a crank member 22. Said crank disk 22 is provided with a crank arm or lug 23 extending outward at an acute angle to the axis of the shaft. Said crank arm 23 is forked to receive a ball 24 which rests in suitable spherical pockets in the outer ends of the crank arm 23, so that said ball may 85 move freely in any direction therein.

The ball 24 is provided with an opening therethrough which receives the arm 20 pivoted to the looper support.

As the main shaft rotates, the crank arm 90 carried on the end thereof, will carry the end of the arm 20 around with it, thus imparting to the looper support, an oscillating movement. The pivotal connection between the arm 20 and the looper support, allows 95 said arm to follow the movements of the ball carried in the outer end of the crank arm. The pivotal connection between the operating arm for the looper support and the looper support, is slightly below the 100 axis of the main shaft, and therefore, the distance which the ball slips outward on the arm 20 when said arm is below the pivotal point, is slightly less than the distance which the ball slides outward on the 105 arm when said arm is above the pivotal point.

The looper is so positioned, that when the arm is above the pivotal point, said looper is being retracted and when the arm is 110

5 moved in a path below the pivotal point, the
looper is moving forward into the needle
loop. For the reasons above noted, a move-
ment in to the needle loop, will be slightly
quicker than the movement out of the needle
loop. When the ball is crossing a horizontal
10 plane passing through the pivotal connec-
tion of the arm with the looper support, said
arm will be moved up and down on its pivot
without imparting any oscillating move-
ment to the looper support.

When the ball is crossing a vertical plane
15 passing through the axis of the shaft, said
arm will receive little or no movement about
its pivotal point, and the looper support will
be oscillated at its maximum speed.

From the above statement, it will be seen
that I have provided a looper movement
20 wherein a looper mounted on a vertical
shaft is driven from a shaft at right angles
thereto by a positive connection, directly
to the shaft and said connection is so con-
structed and arranged that the looper re-
25 ceives a dwell at each end of its stroke, is
moved quickly out of the needle loop, and
is moved still more quickly into the needle
loop.

Having thus particularly described my
invention, what I claim as new and desire
30 to secure by Letters Patent, is:—

1. A looper mechanism including in com-
bination a looper support, a looper carried
thereby, means for supporting said looper
support whereby said looper moves back and
35 forth in a single plane, a looper operating
shaft arranged at right angles to said looper
support, the axis of said looper support and
the axis of said operating shaft lying sub-
stantially in the same plane, and means for
40 connecting said looper support directly to
said looper operating shaft including an
arm pivotally connected to one of said parts
and a second arm rigidly connected with
the other part and coöperating with said
45 first named arm.

2. A looper operating mechanism includ-
ing in combination, a looper support, a
looper carried thereby, means for supporting
said looper support, whereby the looper
50 moves back and forth in a single plane, a
shaft for operating said looper located sub-
stantially at right angles to the looper sup-
port, the axis of said looper support and the
axis of said shaft lying substantially in the
55 same plane, a crank arm carried by said
shaft, an arm pivoted to said looper sup-
port, a ball carried by said crank arm, and
loosely engaging said arm carried by the
looper support.

60 3. The combination with a work support,
of a looper support arranged substantially
at right angles thereto, a looper carried by
said support, a shaft for operating said
looper support located substantially parallel
65 with said work support, the axis of said

looper support and the axis of said shaft
lying substantially in the same plane, and
means for directly connecting said shaft to
said looper support including an arm pivoted
70 to said looper support and a second arm
rigidly connected with said shaft and
coöperating with said pivoted arm.

4. The combination with a work support,
of a looper support arranged substantially
at right angles thereto, a looper carried by
75 said support, a shaft for operating said
looper support located substantially parallel
with said work support, an arm having a
connection with the looper support so as
to move freely in a plane containing the
80 axis of said looper support, and a crank
arm carried by the looper operating shaft,
and engaging the arm carried by the looper
support.

5. The combination with a needle, a
looper moving in a plane substantially at
right angles to the path of said needle, a
support for said looper, an operating shaft
for said looper located substantially at right
90 angles to the looper support, the axis of the
looper support and the axis of the operating
shaft lying substantially in the same
95 plane, and means for directly connecting
said looper support to said looper operating
shaft including an arm pivotally connected
to said looper support so as to swing about
an axis at right angles to the path of the
100 needle, and an arm rigidly carried by said
operating shaft, and coöperating with said
arm on the looper support.

6. The combination with a needle, of a
looper moving in a plane substantially at
right angles to the path of said needle, a
support for said looper, an operating shaft
105 for said looper located substantially at right
angles to the looper support, an arm con-
nected to said looper support so as to move
in a plane longitudinally of the looper sup-
port, and a crank arm carried by said looper
110 operating shaft and engaging the arm on
the looper support.

7. The combination of a needle, of a
looper, moving in a plane substantially at
right angles to the path of the needle, a
support for said looper, an arm pivoted to
115 said looper support so as to swing longi-
tudinally thereof, an operating shaft for
said looper, located substantially at right
angles thereto, and a crank arm carried by
said operating shaft and having a universal
120 sliding connection with the arm on said
looper support.

8. The combination of a looper, moving
in a plane substantially at right angles to
the path of the needle, a support for said
looper, an arm pivoted to said looper sup-
port so as to swing longitudinally thereof,
125 an operating shaft located at right angles
to the looper support, a crank arm carried
by the forward end of said shaft, a ball
130

carried by said crank arm and having free movement therein, said ball slidingly engaging the arm on the looper support.

9. The combination of a needle, a looper moving in a plane substantially at right angles to the path of the needle, a looper support for said looper, spaced bearings carrying said looper support, collars secured to said looper support so as to prevent longitudinal movement of the looper support, said looper support having a flattened portion between said bearings, a forked arm pivoted to said flattened portion of the looper support, an operating shaft arranged at right angles to the looper support, a crank arm carried by said operating shaft, a ball freely mounted in said crank arm, and having a sliding connection with the arm on the looper support.
10. The combination of a needle, of a looper moving in a single plane substantially at right angles to the needle path, a support for said looper, a shaft located substantially at right angles to said looper support, and means for connecting said shaft directly to said looper support including an arm pivoted to the looper support and swinging about an axis at right angles to the path of the needle, and a second arm carried by the shaft and coöoperating with said first named arm, whereby said looper is given a dwell at each end of its stroke, is moved quickly out of the needle loop, and is moved into the needle loop at a speed

slightly faster than the movement of the 35 looper out of the needle loop.

11. The combination of a work support, of a looper support arranged substantially at right angles thereto, a looper carried by said support, a shaft for operating said 40 looper support, the axis of said shaft and the axis of said looper support lying substantially in the same plane, an arm projecting at an acute angle from the end of said operating shaft, and a second arm pivotally connected to the looper support, and means for connecting said second arm to the arm mounted on said shaft.

12. The combination of a work support, of a looper support arranged substantially 50 at right angles thereto, a bracket carrying said looper support, a shaft for operating said looper support, said looper support and said shaft lying substantially in the same plane, means whereby the bracket for the looper support may be adjusted in a direction at right angles to the operating shaft, an arm carried by the forward end of the operating shaft, and extending at an acute angle thereto, a second arm pivoted to the 55 looper support, and a ball connection between said arms.

In testimony whereof I affix my signature, in presence of two witnesses.

LANSING ONDERDONK.
